shown and described.DESCRIPTIONThe FIGURE is a front elevational view of a ceramic flooring tile showing my new design, the rear and side being plain and unornamented. The tile is of a conventional thickness.It is a characterizing feature of the present invention that lines defined by unpatterned areas define a minor rectangle within a larger area of a rectangular tile and that speckled shading is applied in order to shade the minor rectangle oppositely to the major area of the tile.U.S. Patent
